Continuation of application Serial No. 140,681,
May 4, 1937. This application May 18, 1940,
Serial No. 336,053

20 Claims. (Cl. 262—28)

This invention relates to mining apparatus, and more particularly to improvements in coal mining apparatus of the combined horizontal and shear cutter, track supported and guided type.

An object of this present invention is to provide an improved coal mining apparatus having an improved adjustable supporting structure for the kerf cutting mechanism. Another object is to provide an improved adjustable supporting structure for the kerf cutter whereby the latter may be adjusted through a wide range of cutting positions with respect to the coal face. A further object is to provide, in a mining apparatus of the combined horizontal and shear cutter type, an improved adjustable supporting structure for the kerf cutter whereby horizontal kerfs may be cut in the coal face at any desired location between the mine roof and mine floor and vertical kerfs may be cut at any desired location in the coal face between the ribs. Another object is to provide an improved adjustable supporting structure for the kerf cutter whereby horizontal and vertical kerfs may be cut in either rib at either side of the coal face. A still further object is to provide an improved parallel motion supporting structure for the kerf cutter whereby a series of parallel horizontal kerfs may be cut in the coal face at any desired location between a position near the level of the mine floor and a position a substantial distance above the mine floor, and having embodied therein improved means for tilting the kerf cutter relative to the horizontal to change its angle with respect to the horizontal. Yet another object is to provide an improved adjustable kerf cutter supporting structure of the hydraulically operated type whereby the kerf cutter may be readily and quickly adjusted into the desired cutting position and locked in such position. A still further object of this invention is to provide an improved coal mining apparatus of the above character, having novel arrangements and combinations of parts. These and other objects and advantages of the invention will, however, hereinafter more fully appear.

This application is a continuation of my application Serial No. 140,681, filed May 4, 1937.

In the accompanying drawings there are shown for purposes of illustration two forms which the invention may assume in practice.

In these drawings,

Fig. 1 is a plan view of a coal mining apparatus incorporating the preferred illustrative form of the invention.

Fig. 2 is a side elevational view of the mining

apparatus shown in Fig. 1, different positions of the kerf cutter being indicated in dotted lines.

Fig. 3 is an enlarged view in longitudinal vertical section taken substantially on line 3—3 of Fig. 1.

Fig. 4 is an enlarged cross sectional view taken substantially on line 4—4 of Fig. 1.

Fig. 5 is an enlarged view in longitudinal vertical section taken substantially on line 5—5 of Fig. 1.

Fig. 6 is a transverse horizontal sectional view taken substantially on line 6—6 of Fig. 5.

Fig. 7 is a diagrammatic view illustrating the hydraulic fluid system and the associated control means.

Fig. 8 is a diagrammatic side view showing the improved mining apparatus in operative position in a mine, with the kerf cutter adjusted into a top cutting position.

Fig. 9 is a diagrammatic side view showing the mining apparatus in a mine, with the kerf cutter adjusted into a bottom cutting position.

Fig. 10 is a diagrammatic plan view showing the mining apparatus in a mine, with the kerf cutter adjusted into a position for center shearing, the rib shearing position of the kerf cutter being indicated in dotted lines.

Fig. 11 is a diagrammatic view similar to Fig. 8, showing the kerf cutter adjusted into a horizontal cutting position a substantial distance above the mine floor.

Fig. 12 is a plan view of the forward portion of a coal mining apparatus, in which is incorporated a modified form of the invention.

Fig. 13 is a side elevational view of the mining apparatus shown in Fig. 12, different positions of the kerf cutter being indicated in dotted lines.

Fig. 14 is an enlarged view in longitudinal vertical section taken substantially on line 14—14 of Fig. 12.

Fig. 15 is a cross sectional view taken substantially on line 15—15 of Fig. 14.

Fig. 16 is a diagrammatic view illustrating the hydraulic fluid system and the associated control means.

Fig. 17 is a diagrammatic plan view showing the mining apparatus in a mine, with the kerf cutter adjusted for center shearing, the rib shearing position of the kerf cutter being indicated in dotted lines.

Fig. 18 is a diagrammatic side view showing the mining apparatus in a mine, with the kerf cutter adjusted into a bottom cutting position.

Fig. 19 is a diagrammatic side view showing

the mining apparatus in a mine, with the kerf cutter adjusted into a top cutting position.

In both embodiments of the invention there is disclosed a coal mining apparatus of the combined horizontal and shear cutter, track supported and guided type, commonly known as a "universal" track cutter, although it will be evident that various features of the invention may be incorporated in coal mining apparatus of various other types. Also in both embodiments of the invention the improved adjustable supporting structure for the kerf cutter is shown mounted on a self-propelled base, which may be of the same general type as that disclosed in a copending application of one Joseph F. Joy, Serial No. 20,826, filed May 10, 1935, now matured into Patent No. 2,229,087, patented January 21, 1941, although the self-propelled base may assume various other forms such as a slidably supported, flexibly fed base, or a tractor mounted base.

In the preferred illustrative embodiment of the invention disclosed in Figs. 1 to 11, inclusive, the self-propelled base is generally designated 1, and 2 generally designates the improved adjustable supporting structure for a kerf cutter 3. The base 1 comprises a truck frame 4, of a low compact design, supported on truck wheels 5 adapted to travel along a mine trackway 6. Supported on a horizontal portion 7 of the truck frame projecting forwardly in advance of the front truck wheels is a horizontal turntable 8 arranged in a relatively low position on the base with its vertical axis of rotation disposed a substantial distance in advance of the front truck wheels. In certain forms of the invention the turntable 8 may, obviously, be mounted on the base directly above the truck wheel axles, although with such an arrangement, the cutting range of the cutting apparatus is necessarily decreased, unless the supporting structure is more elongated to provide greater over-hang with respect to the base. Mounted on the turntable 8 is an elongated arm or boom structure 9 of the adjustable supporting structure 2 and on the outer extremity of this boom structure the kerf cutter 3 is supported.

The horizontal forwardly projecting frame portion 7 of the truck frame is of generally annular form and supports bearing sleeves 10 in which a circular depending portion 11 of the open-center turntable frame 12 is journaled, the turntable frame maintained in position on its bearings by a retaining ring 13 bolted to the bottom of the turntable frame. The means for rotating the turntable comprises a reversible hydraulic motor 14 of a conventional design, having its power shaft connected to a transverse worm shaft 16 suitably journaled on the truck frame. Fixed to the shaft 16 is a worm 17 meshing with a worm gear rack 18 formed on an arcuate flange 19 integral with the turntable frame. The forward side of the flange 19 is preferably cut away to permit movement of the arm structure down into the cut away portion. The teeth of the worm and worm gear rack are of the self-locking type and lock automatically the turntable in its adjusted position with respect to the base.

Now referring to the arm or boom structure 9 of the adjustable supporting structure 2, it will be noted that pivotally mounted at 20 on the turntable, on aligned horizontal axes extending transversely of the turntable, is a pair of parallel supporting links or arms 21, 21, while pivotally mounted on the turntable at the rear of the

arms 21 on aligned pivotal axes at 22, parallel with the pivotal axes 20, is a pair of parallel links or arms 23. The pivotal axes 22 of the rearward arms 23 are preferably arranged near the rearward edge of the turntable in the manner shown in Fig. 3. The front and rear pairs of arms 21 and 23 are pivotally connected at their outer ends at 24 and 25, respectively, to, and support, an elongated arm or boom portion 26; and these pairs of arms, when in parallel relation, cooperate to provide a parallel motion supporting structure for the boom portion 26, so that when the arms are swung about their inner pivotal axes relative to the turntable, the boom portion is always maintained in a horizontal position. The rear pair of arms 23 are extensible in length and each comprises a hydraulic cylinder 27 containing a reciprocable piston 28 having its piston rod 29 projecting upwardly through the packed upper head of the cylinder. It is accordingly evident that when hydraulic pressure is supplied to the cylinders 27 and the pistons 28 are moved relative to the cylinders, the pairs of front and rear arms are moved out of parallelism, and as a result, the boom portion 26 is tilted about its pivotal connection with the front parallel arms, in vertical planes either upwardly or downwardly with respect to the horizontal. When hydraulic pressure is trapped within the opposite ends of the cylinders, the parts may be locked in their adjusted position. Hydraulically operated means is provided for swinging the pairs of arms 21 and 23 about their pivotal axes relative to the turntable, comprising a pair of hydraulic lifting cylinders 30, 30 disposed at the opposite sides of the boom 26 and mounted to swing in vertical planes, and each cylinder containing, as shown in Fig. 3, a reciprocable piston 31 having its piston rod 32 projecting outwardly through the packed outer head of the cylinder, and the piston rods are pivotally connected at 33 to the boom 26 on aligned axes coincident with the outer pivotal axes of the boom connection with the front pair of arms 23. The lower ends of the cylinders 30 are pivotally connected at 34 to a bracket 35 formed integral with the turntable frame and extending outwardly about the annular portion of the truck frame into connection with the top and bottom portions of the turntable frame, as shown in Fig. 3. When hydraulic pressure is supplied to the lifting cylinders 30, the pistons 31 may be moved to effect swinging of the arms 21 and 23 either upwardly or downwardly about their pivotal axes on the turntable to vary the elevation of the boom portion 26, and by trapping the liquid within the cylinders, the parts may be locked in adjusted position. The means for supplying hydraulic pressure to the cylinders 27 and 30 will be hereinafter described. It will be noted that the cylinders 30 may, if desired, be of the well-known double telescopic type to provide a wider range of adjustment while retaining compactness.

The kerf cutter supporting arm or boom portion 26 comprises a rear motor frame 35, while supported by the front head 36 of the motor frame is an outwardly projecting frame 37 having a cylindric frame portion supporting a bearing sleeve 38 on which a cutter head 39 is rotatably mounted. The cutter head is rotatable about an axis coincident with the longitudinal axis of the boom and the motor axis. Secured to the outer part of the rotatable cutter head is a yoke-shaped frame 40 on which is pivotally mounted at 41, on an axis at right angles to the

cutter head axis to rock relative thereto, a cutter support 42, by which the kerf cutter 3 is carried. Supported by a hanger frame 43 is an elongated plane cutter bar 44 of the kerf cutter, and this cutter bar has guides for circulation about its margin an endless cutter chain 45. The cutter hanger frame 43 is provided with a circular bearing portion 46 journaled on bearing sleeves 47 supported by a circular portion 48 of the tiltable cutter support 42, so that the cutter bar may be swung in its plane into different angular positions with respect to the tiltable cutter support. For locking the cutter bar into its different cutting positions with respect to the tiltable cutter support, there is a slidably guided on the cutter support a locking bar or pin 49 adapted to register with any one of a series of locking apertures 50 formed in the cutter hanger frame; and this locking bar is provided with any suitable form of manual release means 51. Fixed to the forward end of the power shaft 52 of the motor 35 (see Fig. 3) is a coupling member 53 splined at 54 to a shaft 55 journaled in a bearing supported within a bearing support 56 secured to the rotatable cutter head 39 and a bearing supported within the yoke-shaped frame 40 of the cutter head (see Fig. 5). Keyed to the forward end of the shaft 55 is a bevel gear 57 meshing, as shown in Fig. 6, with a bevel gear 58 in turn meshing with a bevel gear 59 keyed to a shaft 60. The shaft 60 is suitably journaled within the yoke-shaped frame 40 and the cutter support and is arranged with its axis coincident with the pivotal axis of the cutter support. Formed on and driven by the shaft 60 is a bevel gear 61 meshing with a bevel gear 62 (see Fig. 5) connected by a multiple disc slip clutch 63 to a shaft 64. This clutch 63 is set at a predetermined clutch loading pressure and is adapted to slip upon overload of the cutter chain. The shaft 64 is journaled within bearings supported within the tiltable cutter support and has keyed thereto at its outer end a chain sprocket 65 which engages and drives the endless cutter chain 45.

Hydraulically operated means is provided for rotating the cutter head 39 relative to the boom 26, comprising a reversible hydraulic motor 66 of a conventional design, having its power shaft connected to an upright worm shaft 67 suitably journaled within bearings supported by a bracket 68 secured to one side of the boom. Fixed to the worm shaft is a worm 69 meshing with a worm wheel 70 formed on an annular frame 71 secured to the cutter head frame. The cutter head is retained in position on the boom by means of a retaining ring 72 bolted to the annular frame 71 and cooperating with an annular flange 73 formed on the outer extremity of the boom. The teeth of the worm and worm gear are of the self-locking type and lock automatically the cutter head in its adjusted position about its axis relative to the boom. The means for tilting the cutter support 42 relative to the rotatable cutter head comprises a hydraulic cylinder 74 pivotally mounted at 75 on projecting lugs 76 integral with the annular frame 71 and containing a reciprocable piston 77 (see Fig. 5). This piston has its piston rod 78 projecting outwardly through the packed front head 79 of the cylinder and is pivotally connected at 80 to a projection 81 formed integral with the tiltable cutter support. It will thus be seen that when hydraulic pressure is supplied to the cylinder 74, the piston 77 may be moved to tilt the cutter support about its pivot 41 relative to the cutter head, and when liq-

uid is trapped within the cylinder, the cutter support may be locked in its adjusted position. The means for supplying hydraulic pressure to the motor 66 and the cylinder 74 will be herein-after described:

It is accordingly evident that when the kerf cutter is in horizontal cutting position with the cutter support pivot axis in parallelism with the arm pivot axes, the lifting cylinders may be operated to swing the pairs of parallel arms 21, 23 in a vertical direction relative to the turntable to effect movement of the kerf cutter through a series of parallel horizontal cutting planes; and when the cylinders of the rearward arms are operated, the boom portion 26 may be swung in a vertical direction about its pivotal connection with the forward pair of arms 21 to tilt the kerf cutter upwardly or downwardly into angularly related cutting planes with respect to the horizontal. It will also be evident that by operating the cutter support tilting chamber 14 and the rear arm cylinders 27, the boom portion 26 may be swung in a vertical direction about its pivotal connection with the outer pair of arms, either upwardly or downwardly with respect to the horizontal, and the cutter support tilted with respect to the boom to adjust the kerf cutter into horizontal cutting planes at the level of the mine roof or at the level of the mine floor. Also by rotating the cutter head about its axis relative to the boom, the kerf cutter may be adjusted into different cutting positions about the head axis relative to the boom. When the kerf cutter is in vertical cutting position, the rear arm cylinders 27 and the lifting cylinders 39 may be operated to swing the boom in a vertical direction to move the kerf cutter in vertical planes; and when the kerf cutter is in horizontal cutting position, the turntable rotating motor may be operated to swing the boom and kerf cutter horizontally in either direction relative to the base.

It will be noted that, if desired, the pairs of parallel arms 21 and 23 may be so arranged with respect to the turntable and boom that when the front arms are in lowered position they rest directly on the top of the turntable frame, and the bottom, at that time, is supported on the top of the turntable. With the parts thus disposed, the forward portion of the boom portion 26 may be tilted downwardly about its pivotal connection with the front arms to locate the kerf cutter at the floor level. With such an arrangement, the double telescopic lifting cylinders, above referred to may be employed to attain the range of adjustment necessary, while still retaining the desired compactness, to effect lowering of the front pair of arms onto the top of the turntable.

Now referring to the hydraulic fluid system and its associated control means, it will be noted that supported on the rearward portion of the truck frame, at the rear of the turntable, is a motor 85 having its power shaft operatively connected to a hydraulic pump 86, and this pump and the propelling mechanism for the base are driven by the motor in the manner disclosed in the above-mentioned Joy application. The pump is submerged in liquid, preferably oil, contained in a tank 87, and the discharge side of the pump, as shown in Fig. 7, is connected by a conduit 88 to the supply passage of a valve box 89, likewise disclosed in the application above-referred to. The discharge passage of the valve box is con-

nected by a conduit 99 back to the tank. The valve box contains a series of manually operable rotary control valves 91, 92, 93, 94 and 95 each having a controlling handle. The valve 91 controls the flow of hydraulic pressure to and the discharge of fluid from the cutter support tilting cylinder 74 through conduits 96 and 97, while the valve 92 controls the flow of hydraulic pressure to and from the head rotating motor 66 through conduits 98 and 99. The valve 93 controls the supply of hydraulic pressure to and from the opposite ends of the lifting cylinders 30 through conduits 100, 101, while the valve 94 controls the supply of hydraulic pressure to and from the rear arm cylinders 27 through conduits 102 and 103. The valve 95 controls the supply of hydraulic pressure and the discharge of fluid from the turntable rotating motor 14 through conduits 104 and 105. It will thus be seen that the various hydraulically operated devices may be operated in either of opposite directions under the individual control of the valves, so that the parts adjusted thereby may be moved in either of opposite directions and locked in such adjusted position by trapping the hydraulic pressure within the hydraulic motors.

The general mode of operation of the form of the invention above described is as follows: The apparatus may be propelled along the mine trackway from one working place to another and during the cutting operation, through the base propelling mechanism driven by the motor 85, in the manner clearly described in the above mentioned Joy application. When the working place is reached and it is desired to cut a horizontal kerf at the floor level in accordance with the arcwall method of cutting, the turntable 8 and boom 9 may be adjusted relative to the base to locate the kerf cutter at one side of the trackway at the level of the mine floor with its tip end at the coal face near the right hand rib. The motor 35 may then be operated to effect circulation of the cutter chain about the margin of the cutter bar, and upon propulsion of the apparatus bodily forwardly along the mine trackway, the kerf cutter is dumped beneath the coal to the position shown in Fig. 9. Upon completion of the dumping cut, the truck wheels are braked, in a known manner, to hold the base stationary with respect to the trackway, and the turntable rotating motor 14 is operated to rotate the turntable 8, thereby to effect swinging of the kerf cutter horizontally in its planes about the turntable axis to effect its transverse cutting operation. When the tip end of the kerf cutter assumes a position adjacent the left hand rib and the swinging cut is completed, the truck wheel brake is released and the apparatus is propelled bodily rearwardly along the mine trackway to effect withdrawal of the kerf cutter beneath the coal. When it is desired to insert a horizontal kerf in the coal face at the roof level, the rear arm cylinders 27 and the lifting cylinders 30 are operated to swing the boom in a vertical direction about its pivotal connection with the pair of outer arms 21, and the cutter head 39 is rotated about its axis relative to the boom to adjust the kerf cutter from the bottom cutting position shown in Fig. 9 to the top cutting position shown in Fig. 8. When the kerf cutter assumes its top cutting position, as shown in Fig. 8, the apparatus may be operated to effect dumping, swinging, and withdrawal movements of the cutter bar in accordance with the arcwall method of cutting, in a manner identical to that above described in connection with

the bottom cut at the floor level. When it is desired to insert horizontal kerfs in the coal face at varying distances with respect to the mine floor, the lifting cylinders 30 may be operated 5 while the pairs of parallel supporting arms 21 and 23 are maintained in parallelism, thereby adjusting the boom in a vertical direction relative to the base while the kerf cutter is at all times maintained in a horizontal cutting position 10 in the manner shown in Fig. 11. By rotating the cutter head 39 about its axis relative to the boom, the kerf cutter may be adjusted from its top cutting position above the head axis, as shown in Fig. 11, to a horizontal cutting position below the head axis. In any of the horizontal cutting positions above described, the kerf cutter may be tilted into angularly related planes with respect to the horizontal by operating the cutter support swinging 74 to swing the cutter support 42 either 15 upwardly or downwardly about its pivot relative to the cutter head 39 and boom. Furthermore, during any of the horizontal cutting operations above described, the kerf cutter may be rocked with the cutter head about the head axis relative to the boom to enable the cutter bar to follow an uneven or rolling bottom or pitching coal seam. When it is desired to insert a vertical shear cut in the coal face, as shown in Fig. 10, the cutter head 39 may be rotated to adjust the 20 kerf cutter into a vertical cutting position with respect to the boom. The kerf cutter may then be swung upwardly by the rear arm cylinders 27 and the lifting cylinders 30, until its tip end assumes a position at the roof level. The apparatus may then be propelled bodily forwardly 25 along the mine trackway to dump the kerf cutter into the coal. The truck wheels of the base may then be braked to hold the base stationary with respect to the trackway, and the rear arm and lifting cylinders 27 and 30 may then be operated 30 to swing the boom in a vertical direction relative to the turntable to move the kerf cutter in vertical planes in an arcuate path to effect a vertical swinging cut. When the tip end of the kerf cutter assumes a position at the floor level, the truck wheel brake may be released and the apparatus propelled bodily rearwardly along the trackway to effect withdrawal of the kerf cutter 35 from the coal. By adjusting the turntable, boom, cutter head and cutter support about their respective pivotal axes, the kerf cutter may be adjusted into positions to cut horizontal and vertical kerfs in either rib at either side of the coal face in an obvious manner. In any of the cutting operations above described, the angular relation of the kerf cutter with respect to the boom may be changed simply by releasing the locking bar 49, swinging the kerf cutter about its pivot, and then relocking the cutter. 40

In the modified form of the invention disclosed in Figs. 12 to 19, inclusive, the portable base, turntable, rotatable cutter head, tiltable cutter support and kerf cutter are similar to those above described; the invention, in this instance, residing primarily in the particular boom structure intervening the turntable and cutter head. The improved boom structure comprises a rear boom portion 106 and a forward boom portion 107, the latter being pivotally mounted on and supported by the rear boom portion. The rear boom portion 106 is pivotally mounted at 108 on a horizontal axis extending transversely of the turntable near the rearward edge of the latter, and the front boom portion 107 is pivotally mounted at 109 on the outer 45

50

55

60

65

70

75

extremity of the rear boom portion on an axis parallel with the pivotal axis 108. The means for swinging the boom in a vertical direction about its pivot relative to the turntable comprises a pair of hydraulic lifting cylinders 110, 111 arranged at the opposite sides of the boom and pivotally mounted at 111 at their lower ends on the turntable frame on aligned axes parallel with the boom pivot axis. These cylinders contain reciprocable pistons 112 having their piston rods 113 projecting forwardly and upwardly through the packed upper heads of the cylinders and pivotally connected at 114 to the forward portion of the rear boom portion 107. For swinging the outer boom portion 107 in a vertical direction about its pivot relative to the rear boom portion, there is provided a pair of hydraulic cylinders 115 arranged at opposite sides of the boom and pivotally mounted at their inner ends on aligned axes coincident with the pivotal axis 108 of the boom. The cylinders 115 contain reciprocable pistons 116 having their piston rods 117 projecting forwardly through the packed outer heads of the cylinders and pivotally connected at 118 to projecting arm-like lugs 119 secured to the front boom portion 107. It will thus be seen that by operating the hydraulic cylinders 110 and 115, the boom may be swung about its pivot 108 and the outer boom portion may be swung into different angularly related positions about its pivot relative to the rear boom portion. Arranged within the rear boom portion is a motor 120 having its power shaft 121 aligned with the longitudinal axis of the rear boom portion, and keyed to the motor power shaft is a bevel gear 122 meshing with a bevel gear 123 keyed to a horizontal shaft 124 coaxial with the pivotal axis of the front boom portion. Meshing with and driven by the bevel gear 123 is a bevel gear 125 keyed to a shaft 126 arranged with its axis of rotation coincident with the longitudinal axis of the front boom portion and suitably journaled on the latter. Keyed to the forward end of and driven by the shaft 126 is the bevel gear 127 which effects drive of the cutter chain, in the manner fully described above. If desired, lifting cylinders 110 may be pivotally mounted on the turntable frame, in the manner shown in Fig. 8, with the upper ends of the piston rods pivotally connected to the boom on aligned axes coaxial with the pivot between the front and rear boom portions, and the cylinders may also be of the double telescopic type to obtain a long range of adjustment while retaining compactness. Also, in this form of the invention, the cylinders 115 may be pivotally mounted at their rear ends on aligned axes parallel with the pivot axis 108, instead of in the coaxial relation disclosed. The means for supplying hydraulic pressure to the hydraulic cylinders will later be described.

It will thus be seen that when the kerf cutter is in horizontal cutting position with the cutter support pivot axis 41 in parallelism with the boom pivot axis 108, the lifting cylinders 110 may be operated to swing the boom in a vertical direction relative to the turntable 3, and the cutter support tilting cylinder 14 operated to tilt the cutter support 42 relative to the boom to move the kerf cutter through a series of parallel horizontal cutting planes between the mine roof and mine floor, the cutter bar being adjustable from its top cutting position, shown in Fig. 13, to its bottom cutting position by rotating the cutter head to move the cutter bar from

above the head axis to a position below the head axis. Further, by operating the cylinders 115 to effect swinging of the outer boom portion relative to the inner boom portion, the cutting range of the kerf cutter may be increased. Also by rotating the cutter head 39, the kerf cutter may be adjusted into different cutting positions about the head axis relative to the boom. When the kerf cutter is in vertical cutting position, the cylinders 110 and 115 may be operated to swing the boom about its pivot 108 and swing the outer boom portion about its pivot relative to the inner boom portion to move the kerf cutter in vertical planes, and when the kerf cutter is in horizontal cutting position and the turntable rotating motor is operated, the boom and kerf cutter may be swung horizontally in either direction relative to the base.

Now referring to the hydraulic fluid system and its associated control means, it will be observed that the pump 86, tank 81, conduits 83 and 90, the valve box 89 and the control valves 91, 92, 93, 94 and 95 are the same as those above described. In this instance, however, the valves 94 and 93 control the supply of hydraulic pressure to and from the opposite ends of the cylinders 110 and 115, instead of to the cylinders 21 and 30, as in the form of the invention above described. Otherwise the hydraulic fluid system is the same as that disclosed in Fig. 7, and therefore a repetition of the description thereof is considered unnecessary. Moreover, the general mode of operation of the mining apparatus of this form of the invention is similar to that described above in regard to the other form of the invention, and therefore a further description of the mode of operation of this form of the apparatus is not necessary herein.

As a result of this invention, it will be noted that an improved coal mining apparatus is provided having an improved adjustable supporting structure for the kerf cutter whereby the latter may be adjusted through a wide range of cutting positions. It will further be noted that by the provision of the improved adjustable supporting structure for the kerf cutter, an improved mining apparatus of the combined horizontal and shear cutter type is provided whereby horizontal kerfs may be cut in the coal face at any desired location between the mine roof and mine floor, and vertical kerfs may be cut in the coal face at any desired location between the ribs, and horizontal and vertical kerfs may be cut in either rib. It will still further be evident that by the provision of the improved adjustable supporting structure for the kerf cutter, an improved coal mining apparatus is provided which is extremely flexible in operation, it being possible not only to adjust the kerf cutter into horizontal and vertical cutting positions but also to roll the kerf cutter about longitudinal and transverse axes to follow an uneven or rolling bottom or a pitching coal seam. Other uses and advantages of the improved coal mining apparatus will be clearly apparent to those skilled in the art.

While there are in this application specifically described two forms which the invention may assume in practice, it will be understood that these forms of the same are shown for purposes of illustration and that the invention may be further modified and embodied in various other forms without departing from its spirit or the scope of the appended claims.

What I claim as new and desire to secure by Letters Patent is:

1. In a mining apparatus, in combination, a portable base, a turntable rotatable upon said base upon an upright axis and having an opening in the top thereof, a kerf cutter, and means for adjusting said kerf cutter through a wide range of horizontal cutting positions including an elongated boom structure, said kerf cutter being pivotally supported on the forward end of said boom structure, and means for supporting said boom structure on said turntable for bodily adjustment upwardly and downwardly between substantially parallel, differently elevated positions and for selectively effecting such adjustments and also at will rearward inclination of said boom structure in its differently elevated positions, said supporting means including link devices pivotally mounted on said turntable respectively at a point adjacent the back of the latter and at a point forward of the rearward edge of said opening, and connected at their opposite ends to said boom structure at points which are both in advance of said second-mentioned point when said boom structure is in lowered horizontal position, the rearward end of said boom structure when said boom structure is horizontal and in lowered position being forward of said first-mentioned point and to the rear of said second-mentioned point whereby upon rearward inclination of said boom structure at various elevations thereof the rearward end of said boom structure is positionable within the opening in the turntable, certain of said link devices having means for varying their effective lengths.

2. In a mining apparatus, in combination, a portable base, a hollow-center turntable on said base, kerf cutting mechanism, and means for adjusting said kerf cutting mechanism through a wide range of horizontal cutting positions including an elongated support arranged with its central longitudinal vertical plane at least substantially bisecting said turntable, the inner end of said support overlying the hollow center of said turntable, said kerf cutting mechanism including a kerf cutter pivotally supported on the outer end of said support, and means for supporting said elongated support upon said turntable and for selectively adjusting it bodily into differently elevated horizontal positions relative to the turntable and for inclining it upwardly or downwardly at its outer end in various elevated positions including its topmost one, and for moving the same when in differently elevated positions to bring its inner end into the hollow center of said turntable, said supporting and adjusting means including adjustable supporting means extending between the turntable and said support and pivotally connected to said support at a point further from the inner end of the latter than the length of said supporting means.

3. In a mining apparatus, in combination, a portable base, a turntable rotatable upon said base upon an upright axis and having an opening in the top thereof, a kerf cutter, and means for adjusting said kerf cutter through a wide range of horizontal cutting positions including an elongated boom structure, said kerf cutter being pivotally supported at the forward end of said boom structure, and means for supporting said boom structure upon said turntable for bodily adjustment up and down between substantially horizontal positions respectively closely ad-

jacent to the top of said turntable and spaced a substantial distance above it and also for tilting of said boom structure when the same is in differently elevated positions to bring the rearward end thereof into the opening in the top of the turntable while said kerf cutter is further elevated, said supporting means including link devices pivotally mounted on the turntable respectively on parallel axes near the rear and near the center thereof and respectively pivotally connected to the boom structure at a point which when the boom structure is in horizontal lowered position is ahead of the center of the turntable and at another point which lies at a distance from the rear end of the boom structure, greater than the length of said link devices which are connected at said last-mentioned point, certain of said link devices having means for altering the effective length thereof.

4. In a mining apparatus, a portable base, a hollow-center turntable on said base, kerf cutting mechanism, and means for adjusting said kerf cutting mechanism through a wide range of horizontal cutting positions including a support overlying said turntable and projecting forwardly from said turntable and also rearwardly over the center of said turntable, said cutting mechanism including a kerf cutter pivotally supported on the forwardly projecting end of said support, and means for supporting said support in different positions upon said turntable including means for adjusting said support bodily upwardly and downwardly through a series of parallel substantially horizontal positions and for adjusting it also when in different ones of such positions, in each case about a transverse axis, to position it, in different angular relations to the horizontal, with its rear end at least partially received in the hollow center of said turntable, said supporting and adjusting means including means acting adjacent the longitudinal center of said support to exert a raising force thereon, and extensible and contractile means acting on said support forwardly of the rear end of the latter to exert a tilting force thereon.

5. In a mining apparatus, the combination comprising a portable base, a horizontal turntable mounted on said base, said turntable having an open center, kerf cutting mechanism, and means for adjusting said kerf cutting mechanism through a wide range of horizontal cutting positions including a frame overlying said base, said kerf cutting mechanism being carried by said frame and including a pivotally supported kerf cutter, and means for supporting said frame in a horizontal position a substantial distance above said turntable and for adjusting said frame when so disposed into a relatively inclined position wherein the rear end of said frame is disposed at least in part within the open center of said turntable, said supporting means including relatively upper and lower adjustable supporting linkage devices on said turntable pivotally connected to said frame on spaced axes in advance of the rearward end of said frame, and means incorporated in certain of said devices for changing the effective length thereof to tilt said frame about one of said axes to position the rearward end of said frame within the open center of said turntable.

6. In a mining apparatus, in combination, a portable base, an open-centered turntable thereon, a kerf cutter, and means for adjusting said kerf cutter through a wide range of horizontal cutting positions including an elongated boom,

said kerf cutter being pivotally supported on the forward end of said boom, and means intermediate said turntable and said boom for adjusting said boom relative to said turntable and supporting it in different adjusted positions including relatively high and relatively low horizontal positions and selectively in inclined positions tilted upwardly and downwardly when in different raised positions, said supporting and adjusting means including link devices supported by said turntable and each connected to said boom at points well forward of the rearward end thereof, means for effecting swinging of said link devices, and means for changing the relative lengths of said link devices, the lengths and the connections of said link devices to said boom and the rearward extension of said boom such as to enable disposition of the rear end of said boom within the open center of said turntable by upward tilting of the forward end of said boom when said boom is in raised position.

7. In a mining apparatus, in combination, a portable base, a turntable rotatable upon said base upon an upright axis and having an opening in the top thereof, a kerf cutter, and means for adjusting said kerf cutter through a wide range of horizontal cutting positions including an elongated boom structure, said kerf cutter being carried at the forward end of said boom structure and mounted thereon for tilting relative thereto about a transverse axis, and means for supporting said boom structure on said turntable for bodily adjustment upwardly and downwardly between substantially parallel, differently elevated positions and for selectively effecting such adjustments and also at will rearward inclination of said boom structure in its differently elevated positions, said supporting means including link devices pivotally mounted on said turntable respectively at a point adjacent the back of the latter and at a point forward of the rearward edge of said opening and connected at their opposite ends to said boom structure at points which are both in advance of said second mentioned point when said boom structure is in lowered horizontal position, the points of said connection of said link devices with said boom structure being located a substantial distance in advance of the rear end of said boom structure and the rear end of said boom structure projecting rearwardly freely of any support other than said points of connection of said link devices therewith, and the rear end of said boom structure when said boom structure is horizontal and in lowered position being forward of said first mentioned point and to the rear of said second mentioned point whereby upon rearward inclination of said boom structure at various elevations thereof said freely projecting rear end of said boom structure is positionable within said opening in said turntable.

8. In a mining apparatus, in combination, a portable base, a hollow-center turntable on said base, kerf cutting mechanism, and means for adjusting said kerf cutting mechanism through a wide range of horizontal cutting positions including an elongated support arranged with its central longitudinal vertical plane at least substantially bisecting said turntable, the inner end of said support overlying the hollow center in said turntable, said kerf cutting mechanism being supported on the outer end of said support and including a kerf cutter pivotally connected to said support for tilting on a transverse axis, and means for supporting said elongated support

on said turntable and for selectively adjusting it bodily into differently elevated horizontal positions relative to the turntable and for inclining it upwardly or downwardly at its outer end in various elevated positions including its topmost one, said supporting means having connection with said elongated support at points spaced a substantial distance forwardly of the inner end of said support with said inner end of said support projecting rearwardly freely of any support other than said points of connection with said supporting means, said supporting means being adjustable to move said support when in differently elevated positions to bring its freely projecting inner end into the hollow center of said turntable, said supporting and adjusting means including adjustable supporting means extending between the turntable and said support and pivotally connected to said support at points of connection which are further from the inner end of said support than the length of said supporting means.

9. In a mining apparatus, in combination, a portable base, a turntable rotatable upon said base upon an upright axis and having an opening in the top thereof, a kerf cutter, and means for adjusting said kerf cutter through a wide range of horizontal cutting positions including an elongated boom structure, said kerf cutter being pivotally supported at the forward end of said boom structure, and means for supporting said boom structure upon said turntable for bodily adjustment up and down between substantially horizontal positions respectively closely adjacent to the top of said turntable and spaced a substantial distance above it, said supporting means having connection with said boom structure at points spaced a substantial distance forwardly of the rearward end thereof so that the rearward end of said boom structure projects rearwardly freely of any support other than said points of connection with said supporting means, said supporting means being adjustable to effect tilting of said boom structure when the same is in differently elevated positions to bring said freely projecting rearward end thereof into the opening in the top of said turntable while said kerf cutter is further elevated, and including link devices pivotally mounted on said turntable respectively on parallel axes near the rear and near the center thereof and respectively pivotally connected to said boom structure at said points of connection one of which when said boom structure is in horizontal lowered position is ahead of the center of the turntable and another point of which lies at a distance from the rear end of said boom structure greater than the length of said link devices which are connected at said last mentioned point.

10. In a mining apparatus, a portable base, a hollow-center turntable on said base, kerf cutting mechanism, and means for adjusting said kerf cutting mechanism through a wide range of horizontal cutting positions including a support overlying said turntable and projecting forwardly from said turntable and also rearwardly over the center of said turntable, said kerf cutting mechanism being supported on the forwardly projecting end of said support, and including a pivotally supported kerf cutter and means for supporting said support in different positions upon said turntable and having connection with said support at points spaced a substantial distance forwardly of the rear end of said support so that said rear end of said sup-

port projects rearwardly freely of any support other than said points of connection, said supporting means including means for adjusting said support bodily upwardly and downwardly through a series of parallel substantially horizontal positions and for adjusting it also when in different ones of such positions in each case about a transverse axis to position it in different angular relations to the horizontal with said freely projecting rear end at least partially received in the hollow center of said turntable, said supporting and adjusting means including means acting adjacent the longitudinal center of said support to exert a raising force thereon and extensible and contractible means acting on said support forwardly of said rear end of the latter to exert a tilting force thereon.

11. In a mining apparatus, the combination comprising a portable base, a horizontal turntable mounted on said base, said turntable having an open center, kerf cutting mechanism, and means for adjusting said kerf cutting mechanism through a wide range of horizontal cutting positions including a frame overlying said base, said kerf cutting mechanism being carried by said frame, and including a pivotally supported kerf cutter and adjustable means for supporting said frame and having connection with the latter at points spaced a substantial distance forwardly of the rear end of said frame and said rear end of said frame projecting rearwardly freely of any support other than said points of connection, said supporting means being adjustable to locate said frame in a horizontal position a substantial distance above said turntable and also adjustable to locate said frame in a relatively inclined position wherein said freely projecting rear end of said frame is disposed at least in part within the open center of said turntable, said adjustable supporting means including relatively upper and lower adjustable supporting linkage devices on said turntable pivotally connected to said frame on spaced axes at said points of connection in advance of the rearward end of said frame, and means incorporated in certain of said devices for changing the effective length thereof to tilt said frame about one of said axes to position said freely projecting rearward end of said frame within the open center of said turntable.

12. In a mining apparatus, in combination, a portable base, an open-centered turntable on said base, a kerf cutter, and means for adjusting said kerf cutter through a wide range of horizontal cutting positions including an elongated boom, said kerf cutter being pivotally supported at the forward end of said boom, and means extending between said turntable and said boom for adjusting said boom relative to said turntable and for supporting said boom in different adjusted positions, said supporting means having connection with said boom at points spaced a substantial distance forwardly of the rear end of said boom so that the rear end of said boom projects rearwardly freely of any support other than said points of connection, said supporting means being adjustable to support said boom in different adjusted positions including relatively high and relatively low horizontal positions and selectively in inclined positions tilted upwardly and downwardly when in different raised positions, including link devices supported by said turntable and each connected to said boom at said points well forward of said rearward end thereof so that said rearward boom end projects freely

rearwardly as aforesaid, means for effecting swinging of said link devices, and means for changing the relative lengths of said link devices, the lengths and the points of connection of said link devices with said boom and said freely projecting rear end of said boom being such as to enable disposition of said freely projecting rear boom end within the open center of said turntable by upward tilting of said boom when said boom is in raised position.

13. In a mining apparatus, in combination, a portable base, a turntable rotatable upon said base upon an upright axis and having an opening in the top thereof, a kerf cutter, and means for adjusting said kerf cutter through a wide range of horizontal cutting positions including an elongated boom structure, said kerf cutter being pivotally supported at the forward end of said boom structure, and means for supporting said boom structure on said turntable for bodily adjustment upwardly and downwardly between substantially parallel, differently elevated positions and for selectively effecting such adjustments and also at will rearward inclination of said boom structure in its differently elevated positions, said supporting means including link devices pivotally mounted on said turntable respectively at a point adjacent the back of the latter and at a point forward of the rearward edge of said opening and connected at their opposite ends to said boom structure at points which are both in advance of said second mentioned point when said boom structure is in lowered horizontal position, the points of connection of said link devices with said boom structure being located a substantial distance in advance of the rear end of said boom structure and the rear end of said boom structure projecting rearwardly freely of any support other than said points of connection of said link devices therewith, and the rear end of said boom structure when said boom structure is horizontal and in lowered position being forward of said first mentioned point and to the rear of said second mentioned point whereby upon rearward inclination of said boom structure at various elevations thereof said freely projecting rear end of said boom structure is positionable within said opening in said turntable, certain of said link devices having means for varying their effective length to effect such inclination of said boom structure.

14. In a mining apparatus, in combination, a portable base, a turntable rotatable upon said base upon an upright axis and having an opening in the top thereof, a kerf cutter, and means for adjusting said kerf cutter through a wide range of horizontal cutting positions including an elongated boom structure, said kerf cutter being pivotally supported at the forward end of said boom structure, and means for supporting said boom structure upon said turntable for bodily adjustment up and down between substantially horizontal positions respectively closely adjacent to the top of said turntable and spaced a substantial distance above it, said supporting means having connection with said boom structure at points spaced a substantial distance forwardly of the rearward end thereof so that the rearward end of said boom structure projects rearwardly freely of any support other than said points of connection with said supporting means, said supporting means being adjustable to effect tilting of said boom structure when the same is in differently elevated positions to bring said freely projecting rear end thereof into the open-

ing in the top of said turntable while said kerf cutter is further elevated, said supporting means including link devices pivotally mounted on said turntable respectively on parallel axes near the rear and near the center thereof and respectively pivotally connected to said boom structure at said points of connection, said points of connection with said boom structure being, when said boom structure is in horizontal lowered position, ahead of the center of the turntable and another lying at a distance from the rear end of said boom structure greater than the length of said link devices which are connected at said last mentioned point, and certain of said link devices having means for altering the effective length thereof to effect tilting of said boom structure as aforesaid.

15. In a mining apparatus, the combination comprising a portable base, a horizontal turntable mounted on said base, said turntable having an open center, kerf cutting mechanism, and means for adjusting said kerf cutting mechanism through a wide range of horizontal cutting positions including a frame overlying said base, said kerf cutting mechanism being carried by said frame and including a pivotally supported kerf cutter, and adjustable means for supporting said frame and having connection with the latter at points spaced a substantial distance forwardly of the rear end of said frame and said rear end of said frame projecting rearwardly freely of any support other than said points of connection, said supporting means being adjustable to locate said frame in a horizontal position a substantial distance above said turntable and also adjustable to locate said frame in a relatively inclined position wherein said freely projecting rear end of said frame is disposed at least in part within the open center of said turntable, said adjustable supporting means including relatively upper and lower adjustable supporting linkage devices on said turntable pivotally connected to said frame on spaced axes at said points of connection in advance of the rearward end of said frame, and means incorporated in certain of said devices for changing the effective length thereof to tilt said frame about one of said axes to position said freely projecting rearward end of said frame within the open center of said turntable, said lower linkage device being pivotally connected to said frame near the forward end of the latter and said upper linkage device being pivotally connected to said frame near the upper part thereof at a point spaced a substantial distance rearwardly of said pivotal connection of said lower linkage device with said frame.

16. In a mining apparatus, a portable base having a circular opening in the top thereof, an annular member supported within said opening for rotation on a vertical axis, an elongated support projecting forwardly from said portable base and having its rearward end extending over said annular member, a cutter bar fixed to the forward end of said elongated support, and means for supporting said elongated support upon said annular member for bodily adjustment into different horizontal positions and also for tilting said support in any of its positions to bring the rearward end thereof downwardly within said annular member, said last mentioned means including link devices pivotally mounted on said annular member on horizontally spaced parallel axes and pivotally connected to said elongated support at points spaced along its length, certain

of said link devices having means for altering the effective length thereof.

17. In a mining apparatus, a portable base having a circular opening in the top thereof, an annular member supported on said base surrounding said opening for rotation on a vertical axis, an elongated boom structure projecting forwardly from said portable base and having its rearward end extending over said opening, a cutter bar fixed to the forward end of said boom structure, and means for supporting said boom structure upon said annular member for bodily adjustment through a series of parallel horizontal positions and for swinging said boom structure about a transverse axis when it is in any of said horizontal positions to position the rear end of said boom within said opening, said last mentioned means including link devices pivotally connected to said annular member and to said boom structure on horizontally spaced parallel axes, certain of said link devices having means for altering the effective length thereof, and extensible means pivotally connected to said annular member in advance of said link devices and pivotally connected to said boom structure for exerting a raising force on the latter.

18. In a mining apparatus, a portable base, a turntable on said base rotatable on a vertical axis and having an open center, an elongated boom structure projecting forwardly from said portable base and having its rearward end extending over the open center of said turntable, a cutter bar fixed to the forward end of said boom structure, and means for supporting said boom structure on said turntable for bodily adjustment within a vertical plane and for swinging said boom structure in any of its adjusted positions about a transverse horizontal axis so that the rear end of said boom moves within the open center of said turntable, said last mentioned means including extensible and contractile devices pivotally connected to said turntable and to said boom on horizontally spaced transverse parallel axes.

19. In a mining apparatus, a portable base, an open-center turntable supported on said base, links pivotally connected to said turntable, a frame to which said links are pivotally connected on aligned axes at points substantially forward of the inner end of said frame, the portion of said frame to the rear of said points and said links of such relative lengths and the pivotal connections of said links to said turntable so located with respect to the latter that the rearward end of said frame may be swung downwardly into the open center of said turntable in any of a wide range of upwardly adjusted positions of said links about their connections to the turntable, means for effecting upward swinging of said links, means also pivotally connected to said turntable and to said frame for selectively effecting either maintenance of said frame in a substantially horizontal position during upward and downward swinging movements of said links or relative swinging between said frame and said links to bring the rear end of said frame into the open center of said turntable, and cutting mechanism pivotally supported on the outer end of said elongated frame.

20. In a mining apparatus, a portable base, an open-center turntable supported on said base, links pivotally connected to said turntable, a frame to which said links are pivotally connected on aligned axes at points substantially forward of the inner end of said frame, the portion of

said frame to the rear of said points and said links of such relative lengths and the pivotal connections of said links to said turntable so located with respect to the latter that the rearward end of said frame may be swung downwardly into the open center of said turntable in any of a wide range of upwardly adjusted positions of said links about their connections to the turntable, means for effecting upward swinging of said links, means also pivotally connected to said turntable and to said frame for selectively effect-

ing either substantially horizontal disposition of said frame at different elevations upon swinging movement of said links, or disposition of the inner end of said frame within the open center of said turntable in differently swung positions of said links, or disposition of said frame in an outwardly and downwardly inclined position, and cutting mechanism pivotally supported on the outer end of said elongated frame.

CHARLES F. OSGOOD.

CERTIFICATE OF CORRECTION.

Patent No. 2,327,928.

August 24, 1943.

CHARLES F. OSGOOD.

It is hereby certified that error appears in the printed specification of the above numbered patent requiring correction as follows: Page 2, second column, line 4, for "prererably" read --preferably--; page 3, first column, line 57, for "annnular" read --annular--; line 74-75, for "pivto" read --pivot--; and second column, line 21, for "chamber" read --cylinder--; line 48, for "bottom" read --boom--; page 4, second column, line 19, after "swing" insert --cylinder--; page 6, second column, line 15, claim 3, after "structure" strike out the comma; page 8, first column, line 26, claim 11, after "frame" strike out the comma and insert the same after "cutter", line 27, same claim; page 9, first column, line 5, claim 14, for "rera" read --rear--; line 7, same claim, before "said" insert --one of--; and second column, line 46, claim 19, for "a" before "open-center" read --an--; and that the said Letters Patent should be read with this correction therein that the same may conform to the record of the case in the Patent Office.

Signed and sealed this 9th day of November, A. D. 1943.

Henry Van Arsdale,

Acting Commissioner of Patents.
